KEY MECHANISM FOR KEY CONTROLLED MACHINES

Original Filed Jan. 10, 1900 4 Sheets-Sheet 4

UNITED STATES PATENT OFFICE

WILLIAM S. GUBELMANN, OF BUFFALO, NEW YORK

KEY MECHANISM FOR KEY-CONTROLLED MACHINES

Original application filed January 10, 1900, Serial No. 1,004. Divided and this application filed November 10, 1916. Serial No. 130,583.

This invention relates to key mechanism for key-controlled machines and is a division of my application Serial No. 1,004, filed January 10, 1900, and eventuating in Patent No. 1,429,201, granted September 12, 1922, to which reference may be had for a complete description of the mechanism controlled by the key mechanism herein described.

One of the objects of the invention is to provide a plurality of keys or manipulative elements each of which is so constructed as to perform several useful functions.

A further object of the invention is to provide, in connection with key locking devices, an arrangement of rows of these improved keys in which any depressed key of its row is released upon the depression of any other key of its row.

I attain the foregoing objects by the mechanism illustrated in the accompanying drawings, the several figures of which are copied in whole or in part from the respective figures of the drawings of said Patent No. 1,429,201, the same reference characters being employed as those employed in designating the same parts in the aforesaid patent. In the accompanying drawings:

Figure 1 is a fragmentary top plan view of my improved key mechanism.

Figure 2 is a vertical longitudinal section of the same, taken substantially in line 2—2, Figure 1, and showing the mechanism in normal or inoperative position.

Figure 3 is a view similar to Figure 2 but with the mechanism in shifted or operative position.

Figure 4 is a fragmentary vertical sectional view showing one of the key levers, and the manner of mounting the same.

Figure 5 is a fragmentary detached view of one of the key levers.

Figure 6 is a fragmentary sectional view of the binding or retaining sleeve for the key levers and their mounting elements.

Figure 7 is a longitudinal sectional elevation, taken substantially in line 7—7, Figure 1, showing principally the shifting keys and associated mechanism.

Figure 8 is a fragmentary longitudinal sectional elevation, taken in line 8—8, Figure

19, and showing the mechanism whereby only one key can be held in a depressed position at a time.

Figure 9 is a fragmentary longitudinal sectional elevation, taken in line 9—9, Figure 19, and showing the mechanism whereby only a predetermined plurality of keys may be in a depressed position at any one time.

Figure 10 is a cross section in line 10—10, Figure 9.

Figure 11 is a fragmentary longitudinal section showing a modification of the mechanism shown in Figure 9.

Figure 12 is a cross section in line 12—12, Figure 8.

Figure 13 is a perspective view of one of the number keys.

Figure 14 is a fragmentary vertical sectional view showing the operating lever, operating shaft, and connected parts.

Figure 15 is a fragmentary transverse sectional elevation, showing one of the shifting keys locked in a depressed position by its special locking mechanism.

Figure 16 is a fragmentary transverse sectional elevation taken in line 16—16, Figure 2, and showing the mechanism for holding the keys in their depressed position and for releasing the same.

Figure 17 is a fragmentary perspective view of the key holding and releasing mechanism.

Figure 18 is a fragmentary vertical section in line 18—18, Figure 16.

Figure 19 is a fragmentary transverse sectional elevation taken in line 19—19, Figure 2.

Like letters of reference refer to like parts in the several figures.

1 represents the main frame of the machine which may be of any suitable construction so as to support the working parts of the machine.

The operation of the desired mechanism (which in the parent case is registering and recording mechanism), is controlled by a number of elbow-shaped key levers which are arranged side by side and pivoted to a transverse supporting rod 35. Each key lever is provided with a lower actuating arm 36

which projects forwardly and an upper stop arm 37 which projects upwardly as represented in Figures 2, 3, 4 and 5. The upper arm of each key lever is provided on its front side with a vertical series of differential stop shoulders 39, which are arranged step fashion and extend from the upper end of this arm downwardly and forwardly thereon; or, in other words, the stop shoulders are arranged radially out of line with one another and different distances from the pivot of the key lever. These stop shoulders of the key lever are adapted to be moved forward and are arranged different distances from their pivot, so that by moving different stop shoulders of the key lever into the path of a movable device (not shown), the latter may be arrested at different points in its movement. The uppermost stop shoulder of the key lever is also the rearmost and therefore requires the greatest forward movement of the key lever, in order to bring this stop shoulder into the path of said movable device.

25 In order to permit the key levers to be readily removed from and inserted in the machine for adjusting the same while assembling the machine, the means for fastening the key levers in the machine are constructed 30 as follows:—

380 (Fig. 6) represents a number of spacing sleeves which are mounted on the supporting rod 35 and which separate the several key levers, as shown in Figures 2, 3 and 35 4. Each of the key levers is provided with a pivot opening 382, which is larger in diameter than the diameter of the supporting rod 35, and a lateral passage or slot 383 which extends from the pivot opening to the outer 40 side of the lever and which is of less width than the diameter of the pivot opening, but greater than the diameter of the supporting rod 35, as shown in Figures 4 and 5. 384 represents a spacing sleeve mounted on the rod 45 35 on one side of the key lever and provided with a concentric bushing 385 which fits into the pivot opening of the key lever. When the parts are assembled the several sleeves and levers bear against one another and the key 50 levers are thereby held on the bushings and compelled to turn thereon concentrically with the supporting rod, but are prevented from becoming detached by reason of the slots in the key levers being narrower than the diameter of the pivot opening and bushing. One 55 of the spacing sleeves, preferably the outermost spacing sleeve 386, arranged adjacent to the frame is provided with a lateral slot 387 extending its full length, as represented in 60 Figure 6, which slot permits this sleeve to be readily placed upon or removed from the supporting rod. When all of the levers and other sleeves have been placed in position, the slotted spacing sleeve 386 is placed on the 65 rod 35 between the pawl arm and frame,

thereby taking up all the slack between the several levers, and sleeves on the supporting rod and holding them in place. When it is desired to remove any one of the key levers, the slotted spacing sleeve 386 is first removed 70 and then the other spacing sleeves and levers are shifted on the rod sufficiently to permit the bushing to be withdrawn from the pivot opening of the key lever which it is desired to remove. When the bushing is thus removed, its key lever can be moved with its slot over the supporting rod and detached therefrom. After the desired fitting of the key lever has been effected the same is first passed with its slot over the supporting rod, 80 the bushing is then inserted in the pivot opening of the key lever and then the sleeves and levers are shoved together and the slotted sleeve 386 is placed on the rod. The sleeve 386 is preferably held in place by a screw 85 388 passing through the frame.

The main number key mechanism.

40 represents the main keys whereby the key levers of the main registering and recording mechanism are operated, and which are guided with their depending stems in the top 41 and bottom 42 of the key-board. As shown in the drawings, nine longitudinal columns of these keys are arranged transversely side by side. The first column on the right hand side of the machine contains seven keys and represents fractions of one-eighth of a cent, the next column toward the left contains nine keys and represents cents and the remaining columns of keys toward the left each contains nine keys and represents progressively higher orders of numbers according to the decimal system, so that the registering keys in the last or left hand column represents hundreds of thousands of dollars.

The lowest numbers of the several columns of keys are arranged transversely in a row on the rear part of the key-board and the corresponding higher numbers of the several columns are arranged likewise in transverse rows and progressively in their order toward the front end of the key-board.

Each of the registering keys is yieldingly held in an elevated position by a spring 43 (Figs. 10, 12, and 16) surrounding the stem of the key and connected at its upper end to the key and bearing with its lower end against the bottom of the key-board. The upper movement of each key is limited by a shoulder 44 formed on the upper part of its stem and engaging with the underside of the top of the key-board, as represented in Figures 16 and 19.

The downward movement of all of the keys is substantially the same, but the arrangement of each column of keys lengthwise of the lower actuating arm of each key lever causes the keys to bear against the lever at

different distances from its pivot so that by depressing different keys the same distance, the key lever will be turned different distances. The keys having the lowest numbers bear against their respective key levers nearest the pivot and consequently the levers are thereby thrown the greatest distance, and the uppermost stop shoulders are shifted into the path of respective movable devices, hereinbefore mentioned but not shown in this application. The throw of each key lever upon depressing any one of its keys is so adjusted, that the proper stop shoulder on its upper arm is moved into the path of the respective movable device, for arresting the latter after it has moved a number of spaces corresponding to the number of the key which is depressed.

The return movement of each key lever is preferably effected by a spring 60 which connects the upper arm of the key lever with the transverse shaft 9, as shown in Figure 3, or with some other convenient part of the machine.

25 *Shifting key mechanism*

A row of special shifting or function-controlling keys is located at the left hand side of the machine.

30 Of these keys, 84, Figures 1, 7 and 9, represents a grand-total or shifting key having a depending stem which is guided in the top and bottom of the keyboard and which bears with its lower end against the upper arm of 35 an elbow lever 80. Upon depressing the key 84, the elbow lever 80 is turned, so as to draw on cords or lines and thereby through suitable mechanism, effect a desired result, which result in the parent application is the printing of a grand-total.

A shifting key 87 having a depending stem which is guided in the top and bottom of the keyboard, bears against the upper arm of the elbow lever 85 which lever may therefore be 45 turned by said key for effecting the performance of a desired function, said function in the parent application being the clearing of a set of grand-total registers.

A shifting key 120 has a depending stem 50 which is guided in the key-board and which engages with the upper arm of an elbow lever 118, as shown in Figure 7. Upon depressing key 120 the elbow lever is turned in the direction for effecting the performance of a desired function, said function in the parent application being the clearing of a set of sub-total registers.

181, is a shifting key provided with a depending stem which is guided in the top and 55 bottom of the keyboard and which engages with the upper arm of an elbow lever 177 which lever is arranged below the bottom of the keyboard and has its lower arm connected by a wire or cord with suitable mechanism for effecting performance of a desired

function, said function in the parent application being the printing of a sub-total.

176 represents a shifting key having a depending stem which is guided in the top and bottom of the keyboard and which engages with its lower end against the upper arm of an elbow lever 174, as represented in Figure 7. Upon depressing key 176, the elbow lever 174 is turned in the direction for effecting performance of a desired function, which function in the parent application, is the preventing of operation of the printing mechanism.

257 represents a shifting key provided with a depending stem which is guided in the top and bottom of the keyboard and which engages with its lower end against the upper arm of an elbow lever 258, as represented in Figure 7. The lower arm of this elbow lever is connected by a line or cord to mechanism for effecting performance of a desired function, which function in the parent application, is the printing of dates.

230 represents a key having a depending stem which is guided in the top and bottom of the keyboard and which bears against the upper arm of an elbow lever 228, said lever being arranged below the bottom of the keyboard and having its lower arm connected with mechanism for performing a desired function, which function in the parent case is the rendering effective of the numbering mechanism.

Each of the number key levers is provided on the front side of its upper arm with a stop or shoulder 194, which is not operatively positioned by any of the number keys. The number key levers are turned simultaneously for bringing all of these shoulders 194 into the paths of the respective movable devices (hereinbefore mentioned but not shown in this application), by means of a rocking plate 195 (Figs. 2, 3, and 7) which is arranged transversely in front of the lower arms of the key levers and overhangs the front ends thereof. This rocking plate is secured to a transverse rock shaft 196 which is journaled in the frame of the machine and which is turned for holding the rocking plate in its uppermost position out of engagement with the key levers by means of a spring 197 as shown in Figure 19. 198 (Fig. 7) represents a shifting key which is provided with a depending stem which is guided in the top and bottom of the keyboard and which engages against the rear end of a rock arm 199 projecting rearwardly from the rock shaft 196. Upon depressing key 198, the rocking plate 195 is turned in the direction for depressing the front arms of all the number key levers and bringing all the shoulders 194 on the upper arms thereof into line which is utilized in the parent application for controlling a plurality of type segments to bring a plurality of horizontal rule types into alignment

115
120
125
130

for effecting ruling or printing of a horizontal line.

Word keys

- 216, Figure 1, represents a row of word-
5 keys or special keys having depending stems
which are guided in the top and bottom of the
keyboard and which engage with and are
adapted to operate a key lever similar to the
key levers of the number key mechanism.
10 This key lever in the parent application
controls the printing of words, abbreviations
or designatory signs in conjunction with the
items printed by the number printing mech-
anisms.

15 *Auxiliary keys*

- 3601, represents auxiliary key levers which
are operated by auxiliary number keys 401,
as shown in Figures, 16 and 19. The details
20 of construction of the key levers 3601 and
the parts co-operating therewith are substan-
tially the same as the construction of the
same parts of the main number key mech-
anism. The auxiliary key mechanism is used
25 in the parent application to control the reg-
istering and recording of numbers separate
from those registered and recorded under
control of the main number key mechanism.

30 *Indicator or detector dials*

- In order to enable the operator to see which
particular character or characters have been
set up after depressing the keys, and thereby
35 to detect any errors in the depression of the
keys, each of the key levers is provided with
an auxiliary dial which is turned forward the
same number of spaces that the key lever has
been depressed and then returns to its initial
40 position when the key lever moves backward
into its normal position. In the preferred
construction of the detector dials shown in
Figure 2, each of these dials consists prefer-
ably of a wheel 238 provided on one side with
45 a pinion 239 which is engaged by a gear seg-
ment 240 secured to the adjacent key lever.
Upon depressing one of the number keys, the
detector dial thereof is turned forwardly
50 by the connecting gearing a number of spaces
corresponding with the number of the key
which has been depressed. If a key lever is
not depressed its detector dial remains at zero.
The detector dial of the word key mechanism
55 is in like manner turned by its key lever so
as to indicate the word or character which
corresponds to the depressed key.

The detector dials of the several key mecha-
nisms are mounted loosely on a transverse
supporting rod 241, as shown in Figure 2.

60 *Key locking and releasing mechanism*

- The keys which have been depressed in the
operation of adding or recording a number,
word or other character are automatically
65 locked in a depressed position until the

adding or recording operation of the partic-
ular number, word or other character has been
completed, and then the depressed keys are
automatically released and permitted to be
raised by their springs.

As shown in Figures 2, 3, 7, 9, 10, 12, 16, 17
70 and 19 the keys are held in a depressed po-
sition by a number of locking plates 327, one
of which is arranged lengthwise on the left
side of the stems of each row of keys. Each
75 of the locking plates is pivoted at its lower
end to the top of the key-board bottom, so
as to swing transversely and is provided along
its upper edge with a number of downward-
facing catches or shoulders 328 which are
80 adapted to engage with upwardly facing
locking shoulders 329 on the stems of the
keys. Each of the keys is provided with a
convex face below its locking shoulder, con-
sisting of a lower rising portion 330 which
85 inclines upwardly and laterally from the
lower part of the key toward the adjacent
locking plate, and an upper receding por-
tion 331 which inclines from the upper end
of the rising portion to the outer end of the
90 locking shoulder 329 of the stem, as shown in
Figures 12, 16, and 19. Each locking plate
is drawn yieldingly with its catches against
the stems of the adjacent rows of keys by
a spring 332, as shown in Figures 9 and 19.
95 The locking catches of the locking plates bear
against the key stems below the convex faces
thereof when the keys are in an elevated po-
sition, as shown in Figure 16. Upon depress-
ing a key, the convex face on its stem deflects
100 the locking plate and when the key has been
depressed fully the respective locking catch
of the locking plate engages with the locking
shoulder 329 of the stem of the depressed
key, thereby retaining the parts which are
105 operated by said key in a shifted position. If
a wrong key has been depressed and the oper-
ator subsequently depresses the right key the
latter during the first part of its downward
movement engages the lower or rising part
110 330 of its convex face with the adjacent lock-
ing catch of the locking plate and disengages
the respective locking catch from the locking
shoulder of the previously depressed key,
thereby releasing the same, as represented
115 in Figure 12. Upon continuing the depres-
sion of the second or correct key after the
first or wrong key has been released, the re-
ceding or upper part 331 of the convex face
of the correct key engages with the adjacent
120 locking catch of the locking plate, thereby
permitting the latter to approach the key
stem and when the correct key has been fully
depressed its locking shoulder is carried be-
low the locking catch of the plate and is en-
gaged thereby, whereby the correct key is
125 locked in a depressed position, as represented
in Figure 19. By this means any incorrectly
depressed key is automatically released by
the depression of the correct key and the lat-
130

ter is in turn automatically locked in a depressed position.

Automatic key release

5 333 (Figs. 2, 3, 7, and 16) represents a transversely movable releasing bar, whereby the keys of the main numbering registering devices are released. This bar is arranged transversely in rear of the rear ends of the 10 locking plates of the main number keys and is guided with its ends in the frame of the machine, as shown in Figures 16 and 18. This bar is provided with a number of upwardly projecting releasing lugs or shoulders 15 334, one of which is adapted to engage with the right (left as viewed in Fig. 16) side of a pin or projection 335 on the rear end of each locking plate 327 of the main registering keys, as represented in Figures 16 and 20 17. Upon shifting the releasing bar 333 toward the left (right as viewed in Fig. 16) its releasing lugs move the main locking plates in the same direction thereby releasing any number keys which are held in a depressed position by the same. The main 25 releasing bar 333 when free is shifted toward the right (left in Fig. 16) into its retracted position by the resilience of the springs which hold the main locking plates in their operative 30 position. The releasing bar 333 is shifted into its operative position by a releasing elbow lever 336 (Fig. 16) which turns on a pivot pin 337 and is connected by its upwardly projecting arm with the releasing bar 333 while its lower arm projects horizontally 35 outward. 338 represents a releasing arm which is arranged lengthwise in the machine and transversely over the lower arm of the releasing elbow lever 336 and which is pivoted at its front end on a pin 339, as represented in Figures 7, 16 and 17. 340 represents a longitudinal releasing lever connected by an upright cord 341 with the rear of the releasing arm 338 and projecting with its rear end 40 into the path of a cross bar 25, as represented in Figure 7.

The transverse bar 25 is supported by two shifting arms 24 which are mounted loosely at their rear ends on the rock shaft or main operating shaft 20 as shown in Figure 7. The transverse bar 25 is arranged at one end in a segmental notch 28 formed in the front part of a rocking frame 15 (Fig. 14), and its opposite end is arranged in a similar segmental notch 28, formed in a rocking frame 29. The frame 15 is secured to the operating shaft 20 on the right-hand side of the machine, and frame 29 is secured to shaft 20 on the left-hand side of the machine.

60 When the machine is at rest, as shown in Figure 7, the transverse bar 25 engages with the front side of the notches 28 in the rocking frames 15 and 29. Upon turning the operating shaft 20 forwardly by means of its handle 21, Figures 7 and 14, the rocking

frames are moved forwardly during the first part of the movement independently of the transverse bar 25. The continued forward movement of the rocking frames causes the rear ends of their notches 28 to engage with the bar 25 and depress the same. 70

The cross bar 25, during the last part of its forward movement with the rocking frames 15 and 29, engages with the releasing lever 340 and depresses the same. The releasing arm 338, during its downward movement with the releasing lever 340, engages with the lower arm of the elbow lever 336 (Fig. 17) and turns the latter so that its upper arm moves the main releasing bar 333 toward the left (right in Figs. 16 and 17) and moves the main locking plates out of engagement with the main number keys, thereby releasing the depressed main keys and permitting them to rise preparatory to setting the machine for performing the next operation of the machine. 80

The row of word keys 216 is arranged on the left-hand side of the main keys and the keys 401 of the auxiliary adding mechanism 90 are arranged on the left-hand side of the word-keys. Each row of word and auxiliary number keys is provided with a locking mechanism similar to those of the rows of main keys. 95

The several shifting keys are arranged in a longitudinal row or column on the left side of the auxiliary keys, and the elbow levers operated thereby are arranged one behind the other, as represented in Figures 7 and 17. 100

342 represents an auxiliary releasing bar whereby the locking plates of the auxiliary keys are released. This bar is arranged transversely of the machine in front of and parallel with the main releasing bar 333 and is adjustably connected therewith, so that the auxiliary releasing bar can be moved into an operative or inoperative position on the main key-releasing bar. 105

As shown in Figure 16, the auxiliary releasing bar is pivoted near its inner end to the main key-releasing bar by a horizontal pivot, and its outer end projects through an opening 343 in the frame, as shown in Figure 18, which permits this bar to be manipulated by the operator from the outside of the frame. The auxiliary releasing bar is held in its raised or lowered position by means of two notches or recesses 344, 345, formed one above the other in this bar and each of which is adapted to be 115 engaged with a pin or projection 346 on the main releasing bar, as shown in Figures 16 and 18, by the resilience of the auxiliary releasing bar which is sufficiently elastic for this purpose. Upon raising the auxiliary releasing bar and engaging its lower recess with the pin 346, the releasing lugs 347 of this bar are carried up to the level of and on the right side of the pins on the rear ends of the locking plates of the auxiliary keys, so that upon 120 130

- moving the main releasing bar toward the left (right in Fig. 16) for releasing the main keys, the auxiliary releasing bar is simultaneously moved in the same direction and disengages the locking plates from the auxiliary keys. When it is desired to repeatedly register or record the same number the auxiliary releasing bar is depressed, so that its lugs 347 are below the pins 335 of the locking plates 10 of the auxiliary keys, this bar being held in this position by engaging its upper recess 344 with the pins 346. Upon now depressing the auxiliary keys of the desired number, said keys will perform their control during the 15 operation of the shaft 20 and frames 15 and 29 but will not be released thereby, so that a single setting of these keys may effect control during a plurality of operations by the operating shaft 20.
- 20 The two columns or rows of word and shifting keys are each provided with a locking mechanism similar to those of the main and auxiliary number keys, but the locking plates of these keys are disengaged from the key 25 stems by a separate releasing mechanism so as to permit the main and auxiliary number keys to be released without releasing the word and shifting keys.

As shown in Figures 16 and 17, the release 30 of the word and shifting keys is effected by a supplemental releasing bar 348 having lugs 349 which engage with the pins 335 on the rear end of the locking plates of the word and shifting keys and which is guided at its 35 outer end in the main frame. The inner end of the supplemental releasing bar is pivoted to the upper arm of a releasing elbow lever 350. This lever is pivoted on the pin 337 and its lower arm projects toward the left (right 40 in Fig. 16) and underneath the releasing arm 338 adjacent to the rear side of the lower arm of the releasing elbow lever 336. When both lower arms of the releasing elbow levers 336 and 350 are arranged underneath the releasing arm 338, the depression of the latter by the rocking frames causes the supplemental releasing bar to be moved toward the left (right in Fig. 16) so that its lugs disengage 45 the locking plates of the word and shifting keys from their respective stems at the same time that the main and auxiliary releasing bars disengage the locking plates of the main and auxiliary number keys from their respective stems, thereby releasing all of the keys 50 simultaneously.

Repeat key

For the purpose of permitting all the word 60 and number keys depressed to remain so during repeated operation of the operating lever 21, the releasing elbow levers 336 and 350 are shifted toward the right (left in Fig. 16) and their lower arms are moved 65 from underneath the releasing arm 338 so that the depression of the lever 340 by the

rocking frames will not affect the releasing elbow levers 336 and 350, thereby retaining the keys in their shifted position. The releasing elbow levers 336 and 350 are moved into operative and inoperative positions by means 70 of a supporting elbow lever 351, as shown in Figures 16 and 17. This lever is pivoted on a stationary bracket 352 and its upper arm carries the pin 337 on which the releasing elbow levers 336, 350 are pivoted. 353 represents an actuating rock lever which engages with its rear arm against the underside of the lower arm of the supporting elbow lever 351. 354 (Fig. 7) represents a repeating shifting key having a depending stem 80 which is guided in the top and bottom of the key-board and which engages with its lower end against the front arm of the actuating rock lever 353. Upon depressing the repeating key, the supporting elbow lever 351 is 85 turned by the actuating lever in the direction for moving the releasing elbow levers, 336, 350 so that their lower arms clear the releasing arm 338 and will not be affected by the depression of the latter. Upon releasing the 90 repeating key the supporting elbow lever 353 is returned to its normal position by a spring 355, shown in Figures 16 and 17, and the releasing elbow levers 336, 350 are shifted into an operative position with their lower arms 95 projecting underneath the releasing arm 338. The releasing elbow lever 350 is turned in the direction for moving the supplemental releasing bar 348 into its retracted position by a spring 356 which is secured to the supporting elbow lever 351. The movement of the elbow lever 350 in this direction is limited by a stop 357 on the supporting elbow lever 351, as shown in Figures 16 and 17.

It is desirable that keys 120, 181, 84 and 87 (Fig. 7) should release all the number keys when any one of said keys is depressed. This is effected by an intermediate elbow lever 358 which is pivoted on the pin 339 and which projects rearwardly over the lower arm of the releasing elbow lever 336 but does not project over the lower arm of the releasing elbow lever 350, as shown in Figures 17 and 7. 359 represents a longitudinal connecting bar connected at its rear end to the lower arm of the intermediate elbow lever 358 and provided with longitudinal slots 360 which receive pins or projections 361 on the lower arms of the elbow levers 118, 177, 80 and 85 and which are operated by the keys 120, 181, 84 and 87 as represented in Figure 7. The pins 361 of the total and zero elbow levers engage normally with the front ends of their respective slots in the connecting bar 359 which causes the latter to be shifted forward 110 by any one of the respective keys without disturbing the others. Upon moving the connecting bar 359 forwardly by the depression of any one of the total or zero keys, the intermediate elbow lever 358 is turned in the direction for depressing its upper arm 115 120 125 130

into engagement with the lower arm of the releasing elbow lever 336, thereby releasing all of the number keys. The depressed word keys and the shifting keys remain depressed 5 until the rocking frames 15 and 29 have completed their forward movement. The locking mechanism of the shifting keys is so constructed that the key 87 cannot be held down by the adjacent locking plate, as shown in 10 Figures 7 and 19.

Special key lock

For the purpose of locking the keys 230, 176 and 354 in a depressed position when 15 it is desired to continue the use of these keys and the mechanism controlled thereby for some time, each of these keys is provided with a movable locking block, 362, as shown in Fig. 7. Each of these blocks is arranged below the top of the keyboard, adjacent to its 20 respective shifting key, and is provided with a thumb piece 363 which is guided in a slot 364 (Fig. 1) in the top of the keyboard, adjacent to the respective shifting key, and 25 projects above the keyboard. Upon retracting the locking block from above the stop shoulder of the shifting key, as shown in Figure 16, the key can rise to its uppermost position. Upon depressing this key and then 30 shifting the locking block so that it is arranged between the stop shoulder 44 of the key and the top of the keyboard, as shown in Figure 15, the key is held in a depressed position.

Key interlocking mechanism

Each column of number and work keys is provided with a locking mechanism which prevents more than one key in each of these 40 columns from being held in a depressed position at the same time. This locking mechanism is best shown in Figures 8, 9, 10, 11, 12 and 15, and is constructed as follows:

365 represents a number of tumblers or 45 blocks arranged in longitudinal rows on the bottom of the key-board each row being adjacent to the right-hand side of the stems of a respective row of number or word keys. These tumblers are capable of a longitudinal movement with references to the column of 50 keys and each set of tumblers is guided on a rod 366 which is supported on the key-board bottom. Each of the tumblers is provided with a convex upper side which preferably 55 slopes or inclines from its higher central part toward the front and rear sides of the tumbler in the form of an inverted letter V. The longitudinal movement of the tumblers is limited by front and rear stops 367, 368 which 60 are engaged by the front and rear tumblers and which also serve to support the guide rod 366 above the bottom 42, as shown in Figure 8. The stem of each number and word key is provided on the side opposite to its locking plate 327 with a follower or spreading head 65 369. The spreading heads of the interme-

diate keys have a convex underside which preferably inclines from its lowest central part to the front and rear sides of the head in the form of the letter V. Each of the spreading heads, except the foremost and rearmost is arranged over the space between two tumblers. The heads of the foremost and rearmost keys are arranged in front and in rear of the foremost and rearmost tumblers respectively and these heads are inclined only on the side facing the adjacent tumbler, as shown in Figure 8. Upon depressing a key in any one of the columns of number or word keys, the spreading head of this key engages with the tumblers on opposite sides thereof and crowds the tumblers in front of the head forwardly and those in rear of the head rearwardly. When the shifting head has been depressed to its fullest extent, the foremost tumbler bears against the front stop 367 and the rearmost tumbler bears against the rear stop 368, and the slack between the several tumblers is fully taken up.

In Figure 8, key number 5 is shown depressed fully and the slack between the tumblers is taken up, in which position of the key its shoulder 329 is engaged by the catch of the adjacent locking plate and is prevented from rising. If key number 5 was depressed erroneously and the correct key, for instance number 3 is subsequently depressed, this correct key moves downwardly idly until it engages or nearly engages the adjacent tumbler and when the correct key reaches this position, its releasing cam or convex face engages with the adjacent locking plate and shifts the same out of engagement with the locking shoulder 329 of the depressed key number 5, as shown in Figure 12, thereby releasing this key and permitting the same to rise. During the continued downward movement of the correct key number 3, the spreading head of the same moves downwardly between the adjacent tumblers and shifts the same so as to take up the slack between them. When the correct key reaches the ends of its downward movement, the same is locked in this position by the adjacent locking plate in the same manner in which key number 5 was previously locked. The slack between the several tumblers is only sufficient to permit of the full depression of one key at a time and the tumblers are so constructed that when two keys are depressed simultaneously these keys are arrested in their downward movement before their locking shoulders are engaged by the locking plate. By this means any one key in a column may be depressed and locked in its depressed position, and if an incorrect key has been depressed, the same is released by the subsequent depression of the correct key, and the correct key is in turn locked in a depressed position, but the locking of two keys at the same time in a depressed position is prevented.

It is sometimes desirable to depress several of the shifting keys simultaneously and lock the same in a depressed position. In the machine as organized no more than three shifting keys require to be depressed and locked at the same time. In order to prevent more than three shifting keys from being locked in a depressed position at the same time, the following mechanism is provided:

370 (Fig. 9) represents a number of tumblers which are arranged in a longitudinal row below the stems of the shifting keys and each of which is secured to the lower end of a flat spring 371 depending from the underside of a supporting bar 372. Each of these tumblers has the form of an upwardly tapering wedge, as shown, and is capable of swinging lengthwise of the column of shifting keys but is held against transverse movement by arranging the depending springs so that their flat sides extend transversely. 373, 374 represent front and rear stops arranged in front and in rear of the foremost and rearmost tumblers 370. 375 represents a number of followers or spreading heads one of which is secured by a flat spring 376 to the lower end of the stem of each shifting key. Each of these spreading heads is preferably cylindrical in form and is capable of swinging lengthwise of the column of shifting keys, but is held against lateral movement owing to the transverse arrangement of the flat supporting spring. Upon depressing any one of the shifting keys its spreading head moves downwardly between the adjacent tumblers and shifts the same forward and backward from opposite sides of the spreading head. The front and rear stops, 373, 374 are so arranged that the slack between the several tumblers is sufficient to allow of full depression of three shifting keys. As shown in Figure 9, the sub-total printing, numbering and dating keys are depressed fully and their followers or spreading heads have been moved between the adjacent tumblers so that the several tumblers bear against each other and against the depressed followers or heads and against the front and rear stops, 373, 374 thereby taking up all of the slack between the tumblers. In order to lock these three keys in a depressed position, the same must be depressed simultaneously. If an additional key, for instance the key 176, is depressed, as shown in Figures 9 and 10, this fourth key is free to move downwardly without disturbing the previously depressed keys until its follower or head engages or nearly engages with the adjacent tumblers and when this fourth key reaches this position its releasing cam engages with the adjacent locking plate 327 and deflects the same, as shown in Figure 12, thereby disengaging the plate from all the

previously depressed keys and causing the same to rise simultaneously. It will thus be seen by this means three keys can be locked in a depressed position and if an error has been made in the depression of one or more of the keys, the subsequent depression of the correct key or group of three keys permits the release of the previously depressed incorrect keys and the locking of the correct keys in a depressed position. If it is desired to permit of locking more or less than three shifting keys in a depressed position, the slack space between the several tumblers must be adjusted accordingly. Instead of supporting the tumblers of the shifting keys from the top, as shown in Figures 9 and 10, the same may be supported by flat springs 377 from the bottom, as shown in Figure 11. If desired the tumblers and followers of the shifting keys may have the form of spheres, as shown at 378 and 379 in Figure 11.

Keys of different color

In order to enable the operator to distinguish the figures or numbers readily on the key-board and thereby enable the same to be manipulated more rapidly, the columns of main figure or number keys are arranged in groups and each group is distinguished by color or otherwise from the adjacent groups. As shown in Figure 1, the keys in the first three columns, representing figures to the right of the decimal point or less than a whole number are indicated in black on a white background; the second three columns of figures from the left of the decimal point to the first pointing off place representing the whole numbers less than thousands, are indicated in white on a black back-ground; and the third three columns of figures from the first pointing off place to the second pointing off place representing the whole numbers between hundreds and millions, are indicated in black on a white background. The words and characters on the word-keys and shifting-keys are also indicated in white on a black back-ground to distinguish them readily from the intermediate auxiliary number keys which are indicated in black on a white background.

In the parent application, the main number key mechanism is shown as controlling a plurality of related accumulators, that is, they are related in the sense that each carries up to the accumulator of next higher order upon completing a revolution, or is carried to by an accumulator of lower denominational order upon the latter completing a revolution. The main number keys are also shown as controlling a plurality of printing mechanisms which are so inter-related that when a higher printing mechanism prints under control of the keys, each of the lower printing mechanisms will be caused to print zero

unless it is itself printing an integer under control of the keys. The auxiliary number key mechanism is shown as controlling similarly inter-related accumulators and printing mechanisms, but the inter-relationship is broken between the accumulators controlled by the main number keys and those controlled by the auxiliary number keys. Also the inter-relationship is broken between the printing mechanisms controlled by the main number keys and those controlled by the auxiliary number keys. By this arrangement the mechanism controlled by either of these sets of keys may be operated an unlimited number of successive times without having any material effect on the mechanism controlled by the other set of keys, i. e. without causing carrying or automatic zero printing by the other accumulators or printing mechanisms.

For a full description of this mechanism, reference is made to my Patent No. 1,429,201, above mentioned.

While I have described the above key mechanism as applied to an adding and recording machine, and the parent application so shows such mechanism, I do not limit myself to adding machines, as the above key mechanism may be utilized to control any mechanisms where such key control is desirable.

I claim as my invention:

1. In a key-controlled machine, the combination of the main frame of the machine, a keyboard frame comprising guideways and being mounted to be relatively immovable with relation to said main frame, a plurality of setting keys mounted for movement in said guideways and each comprising a shoulder, and detaining means comprising a plurality of engaging elements, each engaging element being co-operative with a respective one of the shoulders of said keys for detaining the respective key in set position, said keys and detaining means being so constructed and arranged that the setting of any one of said keys will operate to move the engaging element co-operating with the shoulder of any depressed key out of and considerably beyond engageable relation with the shoulder of the previously depressed key irrespective of momentum, so that the setting of any of said keys releases any other key of said plurality which may have been previously set without dependence on accuracy in the manufacture of parts.
2. In a key controlled machine, the combination of the main frame of the machine, a keyboard frame comprising guideways and being mounted to be relatively immovable with relation to said main frame; a plurality of rows of setting keys mounted for movement in said guideways; a plurality of pivoted locking members, one locking member for each row of a plurality of said rows of keys for locking in set position any key of its respective row; a reciprocating releasing de-

vice comprising a releasing element for each of a plurality of said locking members and operable to effect swinging of said locking members on their pivots for releasing any set keys detained thereby; a main operating mechanism; and means controlled by said main operating mechanism for effecting operation of said releasing device without moving the keyboard.

3. The combination of a plurality of manipulative members operable through substantially uniform extents, an element movable different distances and controllable by each of said plurality of manipulative members, and an element provided with a plurality of differentially arranged stops and controllable by said differentially movable element.

4. In a key-controlled machine, the combination of an element provided with a plurality of differentially arranged stops and, a stepped element controlling movement of said differential stop element, and a plurality of keys which are normally in spaced relation to said stepped element, the construction and arrangement being such that each of said keys upon being moved the same distance as every other of said keys may control movement of said stepped element respective to the key operated.

5. A machine comprising a plurality of keys, a plurality of elbow levers operable by said keys and a plurality of pivot members, one for each of said levers and upon each of which members the respective one of said levers is pivoted, the pivotal portions of all of said levers being arranged in a common plane, and each of said levers being bent so as to lap its next adjacent lever and extend into another common plane in which latter plane each of said levers comes into operative relation with a respective one of said keys, so that the shortest distance from the point of contact of any of said keys with its respective lever to the axial line of the respective pivot member of that lever is greater than the shortest distance between that pivot member and the next adjacent pivot member.

6. In an accounting machine, the combination with a series of depressible keys, of means for detaining said keys in depressed position, and a control element differentially settable by the keys, the construction of the detaining means and the control element being such that when a key is detained in depressed position and the control element thereby adjusted the latter element may be positively readjusted and the detaining means operated to release the detained key upon the operation of another key of the series.

7. A machine comprising mechanism to be controlled, a key movable from normal ineffective position to effective position for controlling said mechanism, automatic means for detaining said key in effective position when

moved to such position, releasing means for operating said automatic means to effect release of said key when detained by said automatic means, and other means for detaining said key in effective position regardless of the operation of said releasing means.

8. In a key controlled machine, the combination of the main frame of the machine, a keyboard frame comprising guideways, a plurality of setting keys mounted for movement in said guideways and each comprising a shoulder, and detaining means comprising a plurality of engaging elements, each engaging element being cooperative with a respective one of the shoulders of said keys for detaining the respective key in set position, said keys and detaining means being so constructed and arranged that the setting of any one of said keys will operate to move the engaging element cooperating with the shoulder of any depressed key out of and considerably beyond engageable relation with the shoulder of the previously depressed key, irrespective of momentum, so that the setting of any of said keys releases any other key of said plurality which may have been previously set without dependency on accuracy in the manufacture of parts.

9. In a key controlled machine, the combination of the main frame of the machine, a keyboard frame comprising guideways, a plurality of setting keys mounted for movement in said guideways and each comprising a shoulder, detaining means comprising a plurality of engaging elements, each engaging element being cooperative with a respective one of the shoulders of said keys for detaining the respective key in set position, said keys and detaining means being so constructed and arranged that the setting of any one of said keys will operate to move the engaging element cooperating with the shoulder of any depressed key out of and considerably beyond engageable relation with the shoulder of the previously depressed key, irrespective of momentum, so that the setting of any of said keys releases any other key of said plurality which may have been previously set without dependency on accuracy in the manufacture of parts, a main operating mechanism correlated with said keys, and means whereby said main operating mechanism may cause operation of said detaining means to release any key detained thereby.

10. The combination with a registering mechanism and a key operated setting mechanism, of a separate hand operated shifting mechanism whereby the registering mechanism is shifted according to the relation of the setting mechanism to the registering mechanism, a plurality of keys whereby said setting mechanism is shifted and each of which is provided with a locking shoulder and a convex cam which is arranged in advance of the shoulder and projects with its salient part

laterally beyond the shoulder, and a plurality of connected catches which are adapted to be engaged by the cams and shoulders of said keys, substantially as set forth.

11. The combination with a registering mechanism and its operating mechanism, of a key lever whereby said operating mechanism is controlled, a row of keys adapted to engage said lever at different distances from its pivot and each key provided on its stem with a cam consisting of a rising portion and a receding portion and provided with a shoulder at the base of the receding portion, and a locking plate provided with catches each of which is adapted to engage with the cam and shoulder of one of said keys, substantially as set forth.

12. In a key mechanism, the combination of a plurality of denominational rows of number keys, and a plurality of rows of keys other than number keys and arranged on each side of said number keys.

13. In a key mechanism, the combination of a plurality of rows of keys of different classes, each of which keys is movable from normal to operative position, a row of said keys of one class being arranged between two rows of keys the class of each of which is different from the class of the intermediate row; and universal means for effecting return to normal position of any keys which may have been moved to operative position in any of said rows.

14. In a key controlled machine, a combination of a main frame, a key board frame fixed with relation to said main frame, key guide ways in said key board frame, rows of setting keys mounted for movement in said guide ways, pivoted locking members associated respectively with said rows of setting keys for locking said keys in set position, a reciprocatory releasing device comprising a releasing element for each of said locking members and effective to swing said locking members on their pivots for releasing any set keys detained thereby, a main operating mechanism in said main frame, connections whereby said main operating devices effects key releasing movement of said releasing device and a manipulative device on said key board frame for effecting releasing movement of said releasing device while said main operating mechanism remains inactive.
